Inventor,
Arthur Burdick

By Frederick L. Fisback
Attorney

UNITED STATES PATENT OFFICE.

ARTHUR BURDICK, OF PITTSFIELD, MASSACHUSETTS.

FUEL SAVER.

Application filed September 18, 1922. Serial No. 583,869.

To all whom it may concern:

Be it known that I, ARTHUR BURDICK, a citizen of the United States, residing at Pittsfield, in the county of Berkshire and 5 State of Massachusetts, have invented certain new and useful Improvements in Fuel Savers, of which the following is a specification.

The present invention relates to auxiliary 10 draft attachments for furnaces, and the object is to provide a simple and practical structure that may be readily applied to a furnace door and will admit a supplemental supply of air above the fire for the purpose 15 of securing more complete combustion of the gases and other products arising from the fire.

In the accompanying drawings:—

Figure 1 is a top plan view of the preferred embodiment of the invention, illustrating the same mounted,

Figure 2 is a longitudinal sectional view on the line 2—2 of Figure 1,

Figure 3 is a front elevation of a portion 25 of the furnace door, with the attachment in place,

Figure 4 is a front elevation of said attachment,

Figure 5 is a view similar to Figure 3, but 30 showing the attachment shifted in order to allow an increased amount of air supplied therethrough.

In the embodiment disclosed, a head is employed, comprising a cylindrical wall 6 35 and substantially flat bottom and top walls 7 and 8. The top wall is provided with a large number of perforations 9, preferably arranged in concentric circles, though the arrangement is immaterial. The head is furthermore provided with a laterally disposed nipple 10 communicating with the internal chamber 11 of said head.

A stem 12 is also provided, this stem tapering toward one end, the smaller end 13 45 being cylindrical in form and detachably telescoping the nipple 10. The outer end of the stem is provided with a transverse wall 14 having a substantially T-shaped opening 15 50 having a horizontal slot 15 and a vertical opening 16 that preferably opens into said slot.

A holding bolt 17 is employed that is adapted to pass through the slot 15 and is provided with spaced washers 18 and 19.

55 Preferably the attachment is mounted on the inner side of a furnace door, a portion

of such door being illustrated at 20. Two openings 21 and 22 are drilled through the door, the former to receive the bolt 17 and the latter to aline with the lower portion of the opening 16. The bolt thus secures the device firmly in place and in substantially horizontal position. The head being disposed above the fire with the perforations 60 uppermost. It will thus be evident that air passing through the opening 22 will flow through the stem 12 and be discharged through the perforations upwardly, with the upgoing products of combustion and thus supplying oxygen that will insure more complete combustion. The amount of air admitted can be readily varied, as indicated in Figure 3 by shifting the stem to one side or the other, thus more or less closing the opening 22 and cutting off the amount of the 65 intake.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. In combination with a furnace door 90 having an air inlet formed therein, a furnace attachment for aiding combustion, comprising a flat hollow head having its upper surface perforated, a tubular tapering stem carrying said hollow head on its smaller end, a plate having a T-shaped slot formed therein carried in the larger end of said tapering tubular stem, and a bolt for projecting through said T-shaped slot to adjustably mount said plate on the furnace door so that 95 the shank of the T may be alined with the air inlet.

2. In combination with a furnace door having an air inlet formed therein, an attachment for aiding combustion comprising 100 a bolt mounted in said furnace door, a plate having a T-shaped slot formed therein adjustably mounted on said bolt so that a portion of the slot may be alined with the air inlet in the furnace door, a tapering stem 105 carried by said plate, the larger end of the same being adjacent the plate, and a flat 110

2
hollow head having its upper face perforated mounted on the smaller end of said stem.

3. In combination with furnace doors having air inlets formed therein, an attachment for aiding combustion comprising a plate having an opening formed therein, means for adjustably mounting said plate on the furnace door so that the opening may be alined with the air inlet, a tapering tubular

stem carried by said plate, the larger end being adjacent the plate, and a hollow head carried by the stem, said head being perforated for directing a current of air upward.

In testimony whereof, I affix my signature **15** in the presence of two witnesses.

ARTHUR BURDICK.
